ATTORNEY

UNITED STATES PATENT OFFICE.

HENRY BOREHERT, OF AURORA, MINNESOTA.

ONE-WHEEL PLOW.

SPECIFICATION forming part of Letters Patent No. 227,723, dated May 18, 1880.

Application filed October 31, 1879.

To all whom it may concern:

Be it known that I, HENRY BOREHERT, of Aurora, in the county of Steele and State of Minnesota, have invented certain new and useful Improvements in One-Wheel Plows, of which the following is a specification.

Figure 1 is a perspective view of the device. Fig. 2 is a view on a line through the seat, showing part of the device in section and part 10 in elevation.

This invention relates to that class of plows known as the "one-wheel plow;" and the novelty consists more particularly in the details of the construction of the parts by which the plow 15 is made movable and the wheel is combined with the plow, all as will now be more fully set out and explained.

In the accompanying drawings, A denotes the plow, and B the plow-beam. C is the 20 wheel, which runs on the horizontal end of the bent axle c. The vertical part of this bent axle is secured to the bent end of the metal bar D, so as to be adjusted up or down by a 25 set-screw in slot c', which clamps it to said bent end. To the horizontal part of this bar D is secured by any suitable means the seat E. This may be attached, as now shown, to a board, e, which can be moved in or out of a 30 slot or socket, d, made in or upon bar D, the other end of said board being carried by an arm, b, flexibly attached to the plow-beam; or the said seat may be placed on said axle in any 35 convenient way so that it can be moved forward or back, according as it is desired to throw the driver's weight on the plow to make it go in or out of the ground.

The board e is so made and attached that without a seat upon it the driver could easily 40 sit thereon, and by changing his position forward or backward cause the plow to work as above described.

To the plow end of the bar D, at the right of seat E, is hinged the frame H at x. This frame is attached by set-screws or in any suitable 45 way to the side of the beam of the plow, and is made of the downwardly-extending piece h, by which it is hinged and attached, as aforesaid, to the side of the beam B, and the strap h' and screw-bolts h".

The strap h' comes outside the beam, and one 50 of the bolts connects it above the beam to the piece h, while the other bolt passes under the beam in like manner. The frame made in this manner can be readily adjusted to a beam of any size and made very firm, and can at will 55 be easily removed or detached.

The horizontal arm h³ of the frame extends inwardly under the axle a short distance, and in the slot h⁴ of this is attached, by nut or otherwise, the lower end of the screw-threaded bar 60 or rod I, which extends down through seat-bar D. Its upper end projects above the bar, and has a wheel or handle, i, by means of which the driver can readily operate it, and so wing the plow down or up at pleasure. As 65 this rod is screw-threaded where it passes through the seat-bar D, it will be held in any position the driver places it, sufficiently sure for all practical purposes. By means of this rod I the driver can operate the hinged frame 70 H at will by merely raising or lowering the arm h³, and in this way the plow can be turned at will.

I am aware that it is not broadly new in one-wheel plows to employ means to level or 75 wing the plow or to adjust the land-wheel; but I do not know that this has been done in the same effectual way as has hereinbefore been set out and explained.

Having thus described my invention, what 80 I consider new, and desire to secure by Letters Patent, is—

1. The combination of seat-bar D, hinged frame H, and screw-rod I with the beam B of plow A, substantially as and for the purposes 85 set forth.

2. In a one-wheel plow, the combination of the plow A and frame H, hinged to the seat-beam D, and adjustable by rod I, with adjustable wheel C, substantially as shown and de- 90 scribed.

In testimony that I claim the foregoing as my own I affix my signature in presence of two witnesses.

HENRY BOREHERT.
